[57] **CLAIM**

The ornamental design for a sterilization cassette, as shown and described.

DESCRIPTION

FIG. 1 is a perspective view of a sterilization cassette in accordance with the invention shown in a closed position;

FIG. 2 is an end elevational view of the cassette shown in FIG. 1, the opposite end elevational view being a mirror image thereof;

FIG. 3 is a rear elevational view of the cassette shown in FIG. 1;

FIG. 4 is a top plan view of the cassette shown in FIG. 1, the bottom plan view being a mirror image thereof;

FIG. 5 is a front elevational view of the cassette shown in FIG. 1;

FIG. 6 is an end elevational view of the cassette thereof, shown in open position, the opposite end elevational view being a mirror image thereof;

FIG. 7 is an end elevational view of a second embodiment of the sterilization cassette, the opposite end elevational view being a mirror image thereof;

FIG. 8 is an end elevational view of the cassette thereof, shown in open position, the opposite end elevational view being a mirror image thereof; and,

FIG. 9 is a perspective view of the cassette shown in

FIG. 8, the cassette shown in the closed position.

*Fig. 1**Fig. 2**Fig. 3**Fig. 4**Fig. 5**Fig. 6*

*Fig. 7**Fig. 8**Fig. 9*
